PANTS CUFF MARKER TEMPLATE

Joseph Kaniuk, 8933 N. Nashville Ave.,
Morton Grove, Ill.

Filed Dec. 26, 1962, Ser. No. 72,948

Term of patent 14 years

(Cl. D52—6)

Fig. 1.

Fig. 2.

Fig. 3.

FIG. 1 is a front view of a pants cuff marker template showing my new design.

FIG. 2 is a side view thereof.

FIG. 3 is an end view thereof.

The rear of the template is the same in appearance as the front.

I claim:

The ornamental design for a pants cuff marker template, as shown and described.
